CLAIM

The ornamental design for a telephone set, as shown
and described.

DESCRIPTION

FIG. 1 is a left front, top and right side perspective view
of a telephone set showing my new design;
FIG. 2 is a perspective view, with the handpiece in-
verted and spaced apart from the stand;
FIG. 3 is a top plan view of the assembled set as shown
in FIG. 1;
FIG. 4 is a bottom plan view thereof;
FIG. 5 is a front elevational view thereof;
FIG. 6 is a rear elevational view thereof;
FIG. 7 is a right side elevational view thereof; and
FIG. 8 is a left side elevational view thereof.

FIG. 1
